(57) **CLAIM**

The ornamental design for a handle for power tools, as shown and described.

DESCRIPTION

FIG. 1 is a rear, first side perspective view of the new design for a handle for power tools in accordance with the present invention;

FIG. 2 is a rear elevation view of the handle for power tools shown in FIG. 1;

FIG. 3 is a side elevation view of the first side of the handle for power tools shown in FIG. 1;

FIG. 4 is a side elevation view of a second side of the handle for power tools shown in FIG. 1;

FIG. 5 is a front elevational view of the handle for power tools shown in FIG. 1;

FIG. 6 is a top plan view of the handle for power tools shown in FIG. 1; and,

FIG. 7 is a bottom plan view of the handle for power tools shown in FIG. 1.

The dot-dot-dash-dot broken lines define the bounds of the claimed design and form no part thereof. The dash-dash-dash broken lines shown in the drawings and the spaces therein are for environmental purposes only and form no part of the claimed design.

1 Claim, 7 Drawing Sheets
